UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

BLINDSTITCH SEWING-MACHINE.

1,132,968.

Specification of Letters Patent. Patented Mar. 23, 1915.

Application filed March 4, 1908. Serial No. 419,092.

To all whom it may concern:

Be it known that I, LANSING ONDERDONK, a citizen of the United States, residing at New York city, in the county of New York, State of New York, have invented certain new and useful Improvements in Blindstitch Sewing-Machines, of which the following is a description, reference being had to the accompanying drawing and to the letters and figures of reference marked thereon.

My invention relates to new and useful improvements in blind stitch sewing machines, and has for its object to provide mechanism for operating the spreader wherein said spreader is given positive movements both in the forward and backward direction, directly from the main shaft in the overhanging arm.

20 A further object of the invention is to provide mechanism for operating the looper, of an overseaming blind stitch mechanism directly from the horizontal shaft, extending through the overhanging arm.

25 Still further objects will in part be obvious and will in part be hereinafter more fully described.

In the accompanying drawings which show by way of illustration one embodiment of my invention: Figure 1 is a side elevation, partly in section, of the forward end of a machine embodying my invention. Fig. 2 is an end elevation, with parts in section and with parts removed showing 35 a sewing machine embodying my invention.

The bed plate 1 of the machine, has rising therefrom a standard 2, on which is supported the usual overhanging arm 3. The work support 4 is also supported on the 40 standard 2, and carries a crimping member 5 at its forward end, which is also provided with feeding teeth, to engage and move the fabric.

The main shaft 6, extends through the 45 overhanging arm, and is operated in any suitable manner. The needle 7 is supported by a needle lever 8 pivoted at the lower end of the feeding portion of the overhanging arm, and is oscillated by means of a link 9 in any suitable manner.

Coöoperating with the needle 7 is a looper 10, which is carried by a looper support 11 mounted in a bearing 12, secured to the overhanging arm by suitable screws 13.

The looper support 10 has an arm 14 secured to its upper end, which arm is provided with a ball stud 15. A link 16 has a universal connection at its lower end with the ball stud 15, and at its upper end said link 16 has a universal connection with a 60 crank arm 17, mounted on the forward end of the shaft 6. The universal connection at the upper end of said link 16 preferably comprises spaced ears 18 between which the link 16 is pivoted and said ears are connected to a stud 19 swiveled in the outer end of the arm 17. The spreader 20 is carried by a suitable spreader support 21 mounted in a bearing 22 secured by suitable screws to the overhanging arm. This support is disposed so as to extend at an angle to a vertical plane containing the longitudinal axis of the work support. A spreader support 70 is provided with an arm 23 at its upper end. Said spreader receives its oscillation 75 from a shaft 24, which is mounted in a bracket 25 carrying an extended bearing 26. The shaft 24 is provided with an arm 27 which is slotted at its forward end to engage a block 28 which block is mounted 80 on a pivot pin passing through the arm 23. The shaft 24 at its upper end is provided with a laterally extending arm 30 which carries a ball stud 31 at its outer end. Said ball stud 31 is connected to one end of an 85 eccentric strap 32 which coöperates with an eccentric 33 upon the main shaft 6.

The operation of my device will be obvious from the above description. The work is supported by the crimping member 90 5 and held thereon by suitable presser feet in the usual manner. The needle 7 moves forward through the fabric bent over the crimping member 5 and the looper 10 is oscillated through the link 16 and the arm 95 17 on the main shaft 6, so that said looper passes through the needle loop and carries its own loop into position for the entrance of the spreader. The spreader 20 is now oscillated by the eccentric 33 and said 100 spreader is carried forward into engagement with the looper thread and carries said looper thread across the line of seam to the opposite side thereof, into position for the needle on its next stroke to enter 105 the looper thread.

It will thus be seen that I have provided mechanism for positively operating the

looper and spreader from the main shaft extending horizontally through the overhanging arm.

Having thus particularly described my invention, what I claim as new and desire to secure by Letters Patent is:—

1. The combination of an overhanging arm, a needle mounted thereon, a work support, a crimping member carried thereby, a main shaft in the overhanging arm, a crank carried by said main shaft at the forward end thereof, a looper supported in a bearing inclined to the vertical and mounted on the overhanging arm, and devices between said crank and said looper for operating said looper.

2. The combination of an overhanging arm, a work support, a crimping member carried by said work support, a needle mounted on said overhanging arm, a looper supported in a bearing inclined to the vertical and mounted upon said overhanging arm, a main shaft located in said overhanging arm, a crank carried by the forward end of the main shaft, a laterally projecting arm carried by said looper support, a ball stud carried by said last named arm, and a link having a universal connection with said ball stud and a crank on the main shaft.

3. The combination with an overhanging arm, a needle mounted thereon, a work support, a crimping member carried thereby, a main shaft in the overhanging arm, a crank carried by said main shaft at the forward end thereof, a looper supported in a bearing inclined to the vertical and mounted on the overhanging arm, devices between the crank and said looper for operating the same, a spreader, a support therefor mounted on the overhanging arm and extending at an angle to a vertical plane containing the longitudinal axis of the work support, an eccentric carried by the main shaft adjacent the forward end thereof, and means co-operating with said eccentric for oscillating said spreader.

4. The combination of a work support, a crimping member carried by said work support, an overhanging arm, a needle mounted on said overhanging arm, and reciprocating back and forth across said crimping member, a spreader co-operating with said needle, a spreader support carrying said spreader, said spreader support being mounted on the overhanging arm, a main shaft located in said overhanging arm, an eccentric on the main shaft adjacent the forward end thereof, a second shaft mounted on said overhanging arm, and operatively connected with said eccentric, and means for oscillating said spreader support from said second shaft.

5. The combination with a work support, of an overhanging arm, a spreader mounted on said overhanging arm, a main shaft lo-

cated in said overhanging arm, an eccentric carried thereby, a second shaft mounted on said overhanging arm, an eccentric strap co-operating with said eccentric and having universal connection with said second shaft, an arm carried by said second shaft and operatively connected to said spreader.

6. The combination with a work support, a spreader, a spreader support mounted on said overhanging arm, a main shaft in said overhanging arm, a second shaft substantially parallel with the spreader support, and operatively connected therewith, and means for operating said second shaft from said main shaft.

7. The combination with a work support of an overhanging arm, a spreader, a spreader support therefor, mounted on said overhanging arm, a main shaft located in said overhanging arm, a second shaft mounted on said overhanging arm substantially parallel with the spreader support and operatively connected therewith, an eccentric on said main shaft and operatively connected with said second shaft.

8. The combination with an overhanging arm, a needle mounted thereon, a looper mounted on said overhanging arm, a main shaft in said overhanging arm, a crank arm carried by said main shaft and operatively connected with said looper, a spreader mounted on said overhanging arm, and an eccentric carried by said main shaft and operatively connected with said spreader.

9. The combination with an overhanging arm, a needle mounted thereon, a looper supported in an inclined bearing upon said overhanging arm, a main shaft located in said overhanging arm, a crank carried thereby, devices between said crank and said looper for operating the latter, a spreader mounted in an inclined bearing upon said overhanging arm, and devices between said spreader and said main shaft for operating the same.

10. The combination with an overhanging arm, a needle mounted thereon, a looper supported in an inclined bearing upon said overhanging arm, a main shaft located in said overhanging arm, a crank carried thereby, devices between said crank and said looper for operating the latter, a spreader mounted in an inclined bearing upon said overhanging arm, a second shaft mounted on said overhanging arm, substantially parallel with said inclined bearing, and operatively connected to said spreader, and means for oscillating said second shaft.

11. The combination with an overhanging arm, a needle mounted thereon, a looper supported in an inclined bearing upon said overhanging arm, a main shaft located in said overhanging arm, a crank carried thereby, devices between said crank and

said looper for operating the latter, a spreader mounted in an inclined bearing upon said overhanging arm, a second shaft mounted on said overhanging arm substantially parallel with said inclined bearing and operatively connected to said spreader, an eccentric on the main shaft, an eccentric strap co-operating therewith and operatively connected to said second shaft.

10 12. The combination of a work support, a crimping member carried thereby, an overhanging arm, a needle mounted on said overhanging arm, a main shaft in said overhanging arm, a looper support carried by

said overhanging arm, a looper mounted to 15 oscillate in said support, means for connecting said looper with said main shaft, a spreader support carried by said overhanging arm, a spreader mounted to oscillate in said spreader support, and means for connecting said spreader to said main shaft. 20

In testimony whereof I affix my signature, in presence of two witnesses.
